UNITED STATES PATENT OFFICE.

EMIL R. KLEMM, OF CHICAGO, ILLINOIS.

DESIGN FOR A LIFTING-JACK CASING.

SPECIFICATION forming part of Design No. 33,374, dated October 16, 1900.

Application filed September 5, 1899. Serial No. 729,559. Term of patent 14 years.

To all whom it may concern:

Be it known that I, EMIL R. KLEMM, a citizen of the United States, residing at Chicago, in the county of Cook and State of Illinois, 5 have invented and produced a new and original Design for a Lifting-Jack Casing, reference being had to the accompanying drawing, forming part thereof.

The figure is a perspective view of my new 10 design for a lifting-jack casing.

As shown in the drawing, the leading or material feature of my design consists of a housing A, having the cut-out portions B and B² and the circular or semicircular side D, 15 with the pedestal portion E, having the ex-

tended and raised length E² and the base H so cut away, substantially as shown at H² and H³, as to form the feet J.

Having described my invention, what I claim as new, and desire to secure by Letters 20 Patent, is—

The design for a lifting-jack casing, substantially as herein shown and described.

Signed by me at Chicago, Cook county, Illinois, this 16th day of August, 1899.

EMIL R. KLEMM.
